UNITED STATES PATENT OFFICE.

JOHN F. BISBACH, OF PLATTEVILLE, WISCONSIN, ASSIGNOR TO ADOLF BRINKMANN,
OF PLATTEVILLE, WISCONSIN.

SCAFFOLD.

1,115,775.

Specification of Letters Patent.

Patented Nov. 3, 1914.

Application filed January 21, 1913. Serial No. 743,322.

To all whom it may concern:

Be it known that I, JOHN F. BISBACH, a citizen of the United States, residing at Platteville, in the county of Grant and State 5 of Wisconsin, have invented certain new and useful Improvements in Scaffolds, of which the following is a specification.

This invention relates to improvements in scaffolds intended for use among painters, 10 paper-hangers and tradesmen or the like and it contemplates the construction of a scaffold that can be partially extended or collapsed while suspended and in use and that for transportation purposes may be completely collapsed or telescoped and then 15 folded about a central hinge and locked when it will occupy a minimum amount of space and can be readily moved from place to place by one or two men.

20 The invention consists in the combination and arrangement of parts to be hereinafter fully described in the following specification, pointed out in the claim and illustrated in the accompanying drawings which 25 form a part of said specification and in which—

Figure 1 is a plan of my improved scaffold in its extended position. Fig. 2 is a side elevation of the same. Fig. 3 is an end 30 elevation. Fig. 4 is a section taken on line 4—4 of Fig. 1. Fig. 5 is a plan of the telescoped scaffold. Fig. 6 is a view of the same when folded about its central hinge and locked.

35 Like reference characters indicate corresponding parts throughout the several views.

The body of my scaffold comprises twin sections each provided with relatively remote heads 1, 1 and united at their adjacent 40 extremities by a hinge 2, which has depending members, the outer ends of which carry the pintle, and which is offset by said arms from the body of the scaffold. Either section comprises a plurality of slats 3, one of 45 which is formed with a plurality of apertures 4. Each end of the body of the scaffold is provided with an extensible coöperating section composed of slats 5 terminally secured in an end piece 6 and extending 50 through the head 1 of said body portion; the slats 5 remote from the end piece 6 are secured to an end piece 7 and are disposed between the slats 3 of the body portion, the end piece 7 being slidably disposed upon

slats 3, this arrangement making the co- 55 operating sections movable with relation to the body sections.

8 is a pin carried by each end piece 7 for locking engagement with the apertured slat 3 whereby the coöperating sections may be 60 locked in an adjusted position with relation to the body of the scaffold. Should it be desired to partially extend or telescope the scaffold while in use it is but necessary to remove pin 8 and then adjust the movable section as desired, replace the pin 8 and the 65 parts are locked in the adjusted position. Each end piece 6 of either coöperating section of the scaffold is provided with a bail 9, one bail being somewhat larger than the 70 other, and to each bail the sustaining ropes 10 are secured by which the scaffold is suspended.

Beneath each head 1 of the scaffold a 75 screw-eye 11 is provided that retains one end of a flexible wire 12 that passes beneath guide blocks 13, also secured to the head 1, and through an eyebolt 14 secured to the hinge-bolt of hinge 2; this wire is to give rigidity to the structure and after the scaffold is collapsed as shown in Fig. 5 and then folded upon the hinge 2 as shown in Fig. 6 80 the flexible wires will also be folded back into the position illustrated in the last named figure. Handles 15 secured to one 85 of the outside slats of the body portion afford a means for readily carrying the scaffold when telescoped and folded. The bailed ends of the scaffold may now be locked together by means of their bails by 90 oscillating said bails into the position shown in Fig. 6.

The members of the hinge 2 have their free ends offset, as shown in Fig. 2, so that the inner edge portions of said members 95 will contact with each other, thus bracing the scaffold frame against caving at the center.

What is claimed is:—

A scaffold comprising companion sections, 100 hinges connecting the inner ends of the sections, each hinge consisting of companion members rigidly connected to the sections, the free ends of the members being offset relatively to each other and projecting laterally of the sections to form braces and being connected to each other by a pintle, whereby 105 the inner edge portions of the hinge mem-

bers will contact with each other to brace the sections when extended, a flexible cable extended across the pintle and means for securing the cable to the sections, the sections being adapted to fold against each other.

In testimony that I claim the foregoing as my own I have hereto affixed my signa-

ture in the presence of two subscribing witnesses.

JOHN F. BISBACH.

Witnesses:

J. F. TIEDEMANN,
S. W. TRABER.
